UNITED STATES PATENT OFFICE

GUNTHER PHILIP WILD, OF PHILADELPHIA, PENNSYLVANIA

DOOR FASTENER

Application filed August 27, 1929. Serial No. 388,693.

This invention relates, generally stated, to door fasteners, especially latch mechanism, for refrigerator doors, cold storage room doors, and the like, as disclosed in my co-pending application for Letters Patent Serial No. 244,568, filed January 5, 1928.

The leading object of the present invention is to provide a door fastener or latch mechanism of the character stated in which is combined simplicity, cheapness, and efficiency of construction and in which a key is provided in contradistinction to a bolt and nut for retaining the spring pressed keeper in place.

A further object of the present invention is to provide a structure of the character stated in which the spring pressed keeper is retained in place by means of an L-shaped block.

A further object of the present invention is to provide a keeper rod having a bevelled cylindrical head at one end and having a rectilinear portion at its opposite end, the intermediate portion of said rod being of reduced cross-sectional area.

A still further object of the present invention is to provide a structure of the character stated in which the L-shaped key or block is provided upon its inner surface with a spring receiving groove arranged upon an arc of a circle.

Other and further objects of the present invention reside in the general details of construction and in the arrangement and combination of parts for attaining the results sought by the foregoing objects.

With these and other objects in view, the invention consists of the novel construction hereinafter described and finally claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as hereinafter shown and described.

The nature, characteristic features and scope of the invention will be more fully understood from the following description taken in connection with the accompanying drawings forming part hereof, and in which:

Fig. 1, is a sectional plan view of a latch mechanism embodying the invention.

Fig. 2, is a view in section taken upon the line 2—2 of Fig. 1.

Fig. 3, is an end view of the keeper casting shown at the left hand side of Fig. 1.

Fig. 4, is a view in section taken upon the line 4—4 of Fig. 3.

Fig. 5, is a view in section taken upon line 5—5 of Fig. 4.

Fig. 6, is a view in side elevation of the keeper detached.

Fig. 7, is a view in perspective of the L-shaped block.

In latching mechanism of the class under discussion, it is customary to secure the spring pressed keeper against undue movement longitudinally considered by means of a bolt and nut connection. Due to the constant slamming of a refrigerator door to which a keeper of the character under discussion is usually applied, the bolt and nut connections become loosened and in fact sometimes the bolt is fractured and actually broken off. According to the present invention I obviate this defect by providing a novel keeper structure now to be described in detail.

In the drawings, the reference numeral 10 designates a door jamb and 11 designates a door as hinged thereto. Fixed to the door jamb 10 as by screws 12 is a casing 13. This casing 13 is provided with a longitudinal bore 14 the inner wall 15 of which bore is provided with an opening 16 for a purpose to presently appear. Arranged within the longitudinal bore 14 of the casing 13 is an endwise shiftable keeper 17 having bevelled portions 18. Extended longitudinally from the keeper 17, and preferably formed integral therewith, is a rod or bar 19, the outer end of which terminates in a relatively large head 20. That portion of the rod 19 arranged intermediate the keeper 17 and the

100

head 20 is cut away as at 21 for a purpose to presently appear. The head 20 extends through an opening in the end of casing 13, as clearly shown in Figs. 1 and 4. Fitted to the opening through which works the keeper stem or rod, and arranged in parallelism with the rod 19, is block 22 of L-shaped cross section, best seen in Fig. 7. The purpose of this block 22 is to prevent lateral movement of the keeper as it moves longitudinally with respect to the casing 13. The block 22, which is L-shaped in cross section, comprises the vertical portion 23 and the horizontal portion 24. The vertical portion 23 is provided with a recess 25 formed upon an arc of a circle to receive one end of a coil spring 26 which is arranged between the keeper 17 and said block 22 and is coiled around the stem 19. In practice the vertical portion 23 of the block 22 abuts against the inner wall of the casing 13 and the part 24 of the block extends through the opening in said wall, as is best seen in Fig. 1. The cut-away portion 21 of stem 19 at its juncture with head 20 forms a shoulder 27 which limits the inward movement of the keeper, as is clearly shown in Fig. 1.

To assemble the above described parts the plunger, including its rod and rectangular head, is inserted within the casing 13. In the connection it is to be noted that the opening at the rear of casing 13 is sufficiently large to permit of the introduction of the head 20 at an inclination so that the shoulder 27 may be dropped down to engage the outer face of casing 13. The spring 26 is then compressed by the operator through opening 16 in casing 13 and held in this position until the block 22 is introduced through the opening in casing 13 to the position shown in Fig. 1, whereupon the operator releases the spring and permits the end coil thereof to seat itself in the groove 25 of the block 22.

Taking up now the latching mechanism as carried by the door 11 and which cooperates with the keeper just described, it is to be noted that the fixed detent 28 is carried by an elongated plate 29, secured as at 30 to a door 11, the fixed detent 28 being secured to the plate 29 by means of rivets 31. Having hinged relation with the plate 29 as at 32 is a movable detent 33, best seen in Fig. 1. The coil spring 34 is interposed between the plate 29 and the detent 33 in order normally to maintain the detent 33 free from the nose of the keeper 17, as is clearly shown in Fig. 1. The stop 35 and adjacent part of the movable detent form a hand grip 36 so that to open the door 11 the operator may grasp the part 36 and pull outwardly upon the detent to thus move the bevelled end of the detent 33 inwardly to engage, ride over, and push outwardly the keeper 17. As the keeper 17 moves to the left in Fig. 1 and as

the operator still pulls upon the door 11, the fixed detent 28 rides outwardly over the receding end of the keeper 17 and thus frees the door 11 for ready opening. As the keeper 17 moves to the left in Fig. 1 and the detent 33 moves around its pivot point, the stop 37, which is preferably formed integral with the detent 33, abuts against the fixed detent 28, thereby limiting the movement of the detent 33.

It is thought that the closing operation of the latching device will be readily apparent without detail description. When the door 11 is in latched position, as seen in Fig. 1, the door may be opened from within a refrigerating room or the like by pushing upon the knob 35 of rod 38 to move outwardly the end 39 of the movable detent 33 and thus compress spring 26 and shift to the left in Fig. 1 the keeper 17, at which time the pin 37 abuts against the fixed detent 28. The function of the stop pin is to arrest the detent movement after its release so as to insure longer life to the coil spring as the latter is apt to break if a too sudden stop action is imposed.

The above described arrangement, construction, connection and combination of parts forms a very efficient and inexpensive refrigerating latching mechanism in which the spring pressed keeper is limited to inward movement by means of the shoulder 27 and in which nuts, bolts, screws, and other securing mediums are eliminated, thus guarding against the loosening of the bolts, nuts and the like and the breaking off thereof, the advantage of which is readily apparent.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I claim as new, and desire to secure by Letters Patent, is:

1. A latch device of the character stated comprising a casing having a relatively large rectilinear opening therein said casing being carried by a door jamb, a keeper the nose of which has opposed bevelled edges, the major part of said keeper being mounted within said casing, a horizontally disposed rod of reduced rectangular cross-section extended outwardly from said keeper nose and penetrating said rectilinear opening in said casing, the extended end of said rod having an enlarged portion of rectilinear cross-section and having a shoulder for engaging the outer face of said casing to limit inward movement of said rod, means including a member of substantially L-shaped cross section the longitudinal axis of which is arranged in parallelism

- with the end of said rod through said relatively large opening in said casing for retaining said rod with respect to said casing, and a spring interposed between the inner end of said keeper nose and said means.
5. 2. A latch device of the character stated comprising a casing having a relatively large rectilinear opening therein, said casing being carried by a door jamb, a keeper the nose of which has opposed bevelled edges, the major part of said keeper being mounted within said casing, a horizontally disposed rod of reduced rectangular cross-section extended outwardly from said keeper nose and penetrating said rectilinear opening in said casing, the extended end of said rod having an enlarged portion of rectilinear cross-section and having a shoulder for engaging the outer face of said casing to limit inward movement
- 10 20 of said rod, means including a block of L-shaped cross section having its lower portion passing in parallelism with the end of said rod through said relatively large opening in said casing for retaining said rod with respect to said casing, and a spring interposed between the inner end of said keeper nose and said means.
- 25 3. A latch device of the character stated comprising a casing having a relatively large rectilinear opening therein said casing being carried by a door jamb, a keeper the nose of which has opposed bevelled edges, the major part of said keeper being mounted within said casing, a horizontally disposed rod of reduced rectangular cross-section extended outwardly from said keeper nose and penetrating said rectilinear opening in said casing, the extended end of said rod having an enlarged portion of rectilinear cross-section
- 30 40 and having a shoulder for engaging the outer face of said casing to limit inward movement of said rod, means including a block of L-shaped cross section having its lower portion passing in parallelism with the end of said rod through said relatively large opening in said casing for retaining said rod with respect to said casing, the rear vertical wall of said block having a groove therein formed upon an arc of a circle to receive the end of a coiled spring, and a spring interposed between the inner end of said keeper nose and said means.
- 45 55 60 65 70 75 80 85 90 95 100 105 110 115 120 125 130
4. A latch device of the character stated, comprising a casing having a relatively large polygonal opening therein said casing being carried by a door jamb, a bolt the nose of which has opposed bevelled edges, the major part of said bolt being mounted within said casing, a horizontally disposed rod of reduced polygonal cross-section extended outwardly from said bolt and positioned in said polygonal opening in said casing, the extended end of said rod having an enlarged head thereon, and having an inner shoulder for engaging the outer face of said casing to limit inward movement of said rod, means passing in parallelism with the end of said rod through said relatively large opening in said casing for retaining said rod with respect to said casing, and a spring interposed between the inner end of said bolt and said means.
